UNITED STATES PATENT OFFICE.

FREDERICK W. KITTLINGER, OF BROOKLYN, NEW YORK.

LAST.

SPECIFICATION forming part of Letters Patent No. 683,606, dated October 1, 1901.

Application filed February 7, 1901. Serial No. 46,333. (No model.)

To all whom it may concern:

Be it known that I, FREDERICK W. KITTLINGER, a citizen of the United States, and a resident of Brooklyn, in the county of Kings 5 and State of New York, have invented a certain new and useful Improvement in Lasts, of which the following is a specification.

The present invention relates to lasts made in separable parts, and has for its main object the provision of means whereby the parts are firmly locked together against relative motion in use as a last and permitting of the ready separation of said parts whenever it is desired to draw the last out of the shoe or 15 boot.

To this and other ends the invention consists of features of construction, details, arrangements, and combinations of devices hereinafter described, and more particularly 20 pointed out in the appended claims.

The preferred form of the invention is illustrated in the accompanying drawings, forming part of this specification, in which—

Figure 1 is a side elevation, partly in section along the central vertical plane of the last, of a last in which the invention is embodied; and Fig. 2 is a plan, partly in section, of the same.

In the drawings the reference-letter *a* indicates a sole or lower section, and *b* an upper or instep section, of the last, the upper surface of section *a* and the lower surface of section *b* fitting against each other, as shown. The section *a* is provided with a vertical centrally-located longitudinal slot *c*, so placed as to be covered by section *b*. Immediately in rear of and overhanging or overlying part of slot *c* is a keeper, which is conveniently formed of a button *d*, whose shank is driven into the section *a*. This button *d* is preferably rounded on top and by preference is beveled or undercut underneath for a purpose presently to appear. The keeper may be flush with or project above the surface at the top side of the section *a*, or it may be otherwise arranged or constructed. The section *b* is slotted for a distance along its central vertical longitudinal plane, as indicated at *e*, and is recessed at *f* to receive or fit over the button *d*. The 45 recess *f* is also extended upwardly into section *b* for a purpose presently to appear. The slots *c* & *e* lie in the same plane in the assem-

bled last. A catch *g* fits in section *b* in slot *e*, being held in place by a pivot-pin *h*. The working end *i* of the catch is so located that 55 its flat working face *i* engages with the bevel or undercut edge of the keeper, surface against surface. A spring *k* is placed in recess *f* behind the catch *g* and presses the catch into engagement with the button or keeper, as above set forth. The catch *g* is prolonged above the pivot *h* and is shaped to coact with the bottom of the slot *e* for the purpose of retaining the end *i* in position to coact with the rounded-off top of the button 65 *d*, which presses the catch toward the toe of the last as the parts are assembled, the catch ultimately snapping under the button or keeper as the section *b* moves into place upon section *a*. 70

The section *b* may be held against motion forwardly and transversely of the last by any suitable means—as, for example, the means shown in the drawings. Thus the front end of the section *b* may be so held by forming it 75 with a V shape at *l*, fitting under an undercut counterpart on the section *a*, while the catch *g* and slot *c* or the recess *f* and button *d*, or both, may be used to prevent lateral motion of the rear end of section *b*. The de- 80 scribed last forms a rigid structure over which the leather may be stretched without in any wise causing relative lateral motion of sections *a* & *b*, whereby misshapen products are avoided. By pressing on the catch *g* at 85 a point above the pivot *h* it may be moved backward, thus moving the working end *i* toward the toe of the last and disengaging it from the keeper, after which the section *b* may be removed from the boot or shoe by an 90 upward and backward pull on the section. Section *a* may be withdrawn thereafter in the usual manner.

It is preferable that all parts of catch *g* except end *i* be wholly within the section *b*. In 95 such a case the section *b* is provided with a transverse perforation *m* just in rear of the front edge of the catch *g*—that is, the catch *g* projects so far into the hole *m*, which crosses slot *e*, that the hook usually employed 100 by workmen for drawing out lasts when it is inserted in hole *m* engages with the front edge of the catch *g* and moves the end *i* forwardly or toward the toe of the last so far as

to disengage it from under the keeper, after which an upward and rearward pull on the hook draws out the section *b*, or the hook may so move the end *i* that some force will 5 still be required to disengage the end *i* from the keeper as the section *b* is drawn out, or the catch may be wholly disengaged from the keeper by the hook and the walls of the recess *f* fit down about the button closely, so 10 that section *b* must be lifted somewhat as it is withdrawn from the shoe or boot, so as to pass over the button, or the button may be flush with the surface of the top side of the section *a*, and in such case the catch and 15 slot *c* do the work of preventing lateral motion of the rear of section *b*.

The invention may be embodied in forms other than that illustrated in the drawings and above described without departing from 20 the spirit of my invention. I do not therefore limit my claims to the precise form of the invention shown in the drawings and above described.

What I claim as new, and desire to secure 25 by Letters Patent of the United States, is—

1. The combination of a sole-section *a*, an instep-section *b*, a rounded-off circular button *d* secured to and projecting above the top side of the section *a*, said section *a* hav-

ing a recess or slot *c* forward of and below 30 the button *d*, a recess in section *b* adapted to fit closely around the button *d*, a catch *g* pivoted to section *b* and adapted to enter slot *c* and engage under the button *d*, and a spring in said recess in section *b* for actuating the 35 catch *g*, substantially as described.

2. In a last, the combination of sole and instep sections *a* *b*, a rounded top button *d* on and projecting above the top side of section *a*, said section *a* having a slot forward of and 40 under the button, a catch *g* in a slot in section *b* and having a working end *i* projecting below section *b*, a pin connecting catch *g* and section *b* and said section *b* having a recess which fits closely over the button *d*, a 45 spring in said recess behind the catch and acting thereon, a transverse perforation in the section *b* into which the upper end of catch *g* projects, and means for preventing the forward end of section *b* from moving 50 laterally, substantially as described.

Signed at New York city, in the county of New York and State of New York, this 6th day of February, A. D. 1901.

FREDERICK W. KITTLINGER.
